UNITED STATES PATENT OFFICE.

EDWARD R. SOLLIDAY, OF LAMBERTVILLE, NEW JERSEY.

PAD FOR COPYING-BOOKS.

SPECIFICATION forming part of Letters Patent No. 451,340, dated April 28, 1891.

Application filed September 21, 1887. Serial No. 250,331. (No specimens.)

To all whom it may concern:

Be it known that I, EDWARD R. SOLLIDAY, of Lambertville, in the county of Hunterdon, and in the State of New Jersey, have invented 5 certain new and useful Improvements in Pads for Copying-Books; and I do hereby declare that the following is a full, clear, and exact description thereof, reference being had to the accompanying drawings, in which—

10 Figure 1 shows a perspective view of a copy-book open and with one of my improved pads in place therein, and Fig. 2 a similar view of the pad removed from the book.

Letters of like name and kind refer to like 15 parts in each of the figures.

The object of my invention is to provide an improvement in pads for use in copying-books; and to this end my invention consists in the pad constructed and arranged as hereinafter specified.

20 In moistening-pads as heretofore made for use with copying-books the corners of the pad have been cut off to prevent any pressure upon direct contact of the moistening- 25 surface with the corners of the leaves being treated. Such pads, however, have been defective and objectionable in that they were not so constructed as to prevent access of moisture to the exposed corners of those leaves 30 behind the pad which it was not intended to moisten. In order to prevent this undesirable wetting of leaves back of the moistening-pad, a separate sheet of oiled paper or other water-proof material had to be used.

35 The special object of my invention has been to produce as a single article of manufacture a complete pad which, without the aid of the separate oiled sheet, will moisten the leaves as desired without causing pressure 40 to be brought to bear on thin corners and without any possibility of the undesirable wetting of the leaves not in front of the pad.

In the drawings, A designates a copy-book which can be of any well-known form, construction, or manufacture, and B designates 45 one of my improved pads therein.

As shown in Figs. 1 and 2, this pad is one of blotting-paper, and has a back or holder C of water-proof material, such as is used in 50 the well-known "Chadwick" copying-book, where it is desired to keep some of the leaves

of the book damp ready for use; and the pad is therefore kept wet. At its sides this back or holder C is, as shown, formed with narrow pockets, into which the edges of the sheet or 55 connected sheets of blotting-paper project and by which they are held.

As shown in the drawings, the corners of the pad proper, as distinguished from the back or holder, are cut off. The corners of the 60 back are left uncut, as shown, so that the leaves of the book behind or below the pad may be kept entirely separated from the damp leaves on the other side of the pad. I do not limit myself to the cutting off of any particular ones or number of the corners.

Where the pad is to be put in the book always in one way it is sufficient if the outer corners only are cut off. If desired, only one of the outer corners need be cut, as this will 70 insure that the leaves at that one corner will not be subjected to pressure, and consequently that they will not stick together there, but can be easily separated when the book is to be opened at any page. Where both the 75 upper and lower outer corners of the leaves are treated with a preparation to make them impervious to moisture, both such corners of the pad should be cut off, so as to relieve the prepared leaf-corners of pressure during the 80 use of the book in copying. As indicated hereinbefore, this relieving of the treated corners from pressure prevents the sticking or adhering together which is liable to occur 85 when they are pressed into close contact with each other, and also the squeezing of moisture from the leaves.

I do not limit myself to any material for or way of manufacturing the pad, as my invention has merely to do with the forming of 90 the pad, so as to prevent pressure upon portions of the leaves of the copying-book where pressure is undesirable or injurious and the wetting of the corners of the leaves back of the pad by moisture passing around the cut 95 corners of the latter.

If desired, instead of cutting a corner of the absorbent or moisture-receiving part of the pad entirely off, a portion of it can be cut away so as to reduce the thickness of the pad 100 at that point. This will prevent undue pressure upon the leaves above the reduced por-

tion. Such cutting away or thinning of the corner is entirely within the scope of and involves no departure from my invention.

Having thus described my invention, what I claim is—

A moistening-pad for use in copying-books, having the body of moisture-holding material cut away at one or more of its corners, and an attached water-proof back having its corners uncut, substantially as shown and de-

scribed, so as to separate the sheets or leaves back of the pad entirely from the ones being moistened.

In testimony that I claim the foregoing I have hereunto set my hand this 17th day of 15 September, A. D. 1887.

EDWARD R. SOLLIDAY.
